[57] CLAIM

The ornamental design for a bicycle wheel, as shown and described.

DESCRIPTION

FIG. 1 is a front perspective view of the bicycle wheel of the present invention;

FIG. 2 is a side view in elevation of the bicycle wheel of FIG. 1, it being understood that the opposite side is substantially a mirror image thereof;

FIG. 3 is a front view in elevation of the bicycle wheel of FIG. 2;

FIG. 3A is a sectional view of the bicycle wheel of FIG. 2 at 3A;

FIG. 4 is a top view of the bicycle wheel of FIG. 2; and, FIG. 5 is a bottom view of the bicycle wheel of FIG. 2.
